Primary Examiner — Rebekah A Caruso*(74) Attorney, Agent, or Firm* — Rankin, Hill & Clark LLP(57) **CLAIM**

The ornamental design for a beauty tool switch, as shown and described.

DESCRIPTION

FIG. 1 is a perspective view of a beauty tool switch;

FIG. 2 is a right side elevation view thereof;

FIG. 3 is a left side elevation view thereof;

FIG. 4 is a top plan view thereof;

FIG. 5 is a close up perspective view thereof;

FIG. 6 is a close up right side elevation view thereof;

FIG. 7 is a close up left side elevation view thereof; and,

FIG. 8 is a close up top plan view thereof.

The broken lines in the drawings depict portions of the article that form no part of the claimed design.
